ELECTRIC PORTABLE MASSAGER

Clifford Edward Grube, 8816 Merrill Ave.,
Niles, Ill. 60648

Filed Feb. 14, 1966, Ser. No. 1,034

Term of patent 14 years

(Cl. D83—1)

FIGURE 1 is a fragmentary perspective view of the upper portion of my electric portable massager;

FIGURE 2 is a modified embodiment of the massager shown in FIG. 1, wherein the only difference resides in the inclusion of a panel plate;

FIGURE 3 is a side elevation of the massager shown in FIG. 1;

FIGURE 4 is a top end view thereof;

FIGURE 5 is a fragmentary elevational view of the upper portion thereof showing the side opposite to that shown in FIG. 3; and

FIGURE 6 is a fragmentary bottom end view of the upper portion thereof.

I claim:

The ornamental design for an electric portable mas- sager, substantially as shown and described.
